H. H. WALCK.
LOCOMOTIVE CROSS HEAD GUIDE.
APPLICATION FILED FEB. 10, 1916.

Patented July 4, 1916.

UNITED STATES PATENT OFFICE.

HUGH H. WALCK, OF CHAMBERSBURG, PENNSYLVANIA.

LOCOMOTIVE-CROSS-HEAD GUIDE.

1,189,318.

Specification of Letters Patent.

Patented July 4, 1916.

Application filed February 10, 1916. Serial No. 77,515.

To all whom it may concern:

Be it known that I, HUGH H. WALCK, a citizen of the United States, and resident of Chambersburg, in the county of Franklin, and in the State of Pennsylvania, have invented a certain new and useful Improvement in Locomotive-Cross-Head Guides, and do hereby declare that the following is a full, clear, and exact description thereof.

10 My invention relates to locomotive cross head guides, and the object of my invention is to provide an adjustable construction which will enable that adjustment which is necessary to compensate for wear, to be 15 easily and rapidly performed, while at the same time providing a construction of the durability and strength which locomotive usage necessitates. Government regulations respecting the extent of looseness that may 20 be allowed in a locomotive cross-head are strict and rigidly enforced, and it requires from one to three hours to make the adjustments that are required to compensate for wear with the guide construction now in 25 use. The importance and desirability of an efficient and quickly operable adjusting means will be evident.

With the object stated in view, my invention consists in the adjustable cross head 30 guide constructed substantially as herein-after specified and claimed, and an embodiment of my invention is shown in the accompanying drawings in which—

Figure 1 is a perspective view of such a 35 cross head guide; Fig. 2 a similar view showing certain of the parts separated; Fig. 3 is a longitudinal section showing the parts assembled; Fig. 4 is a cross section on the line 4—4 of Fig. 3.

40 A locomotive cross head has two guides, an upper and a lower one, but adjustment for wear is preferably made only at the lower guide because any adjustment of the upper guide may derange the cylinder valve 45 mechanism, and while my construction can be used, both for upper and lower guides, I will describe the construction with reference to its use as a lower guide, but with the understanding that I do not limit myself to 50 its use for the lower guide, because, as I have just stated, it can be used for both upper and lower guides.

Proceeding now with the description of 55 the construction with reference to the lower guide, it will be found that I employ as a base, or fixed member, a horizontal bar 10,

which, at its opposite ends is respectively bolted to the cylinder head H and the yoke Y, the opposite ends of the bar being preferably reduced in thickness for the convenient application of the fastening bolts, and in its upper side said bar 10 has a recess 110 which is of a length that at each end stops a little short of the reduced ends of the bar, and is of a width equal to the width of the bar, and in said recess is placed the cross head wear-receiving member 11, which for purpose of distinction I shall refer to by the designation block. The block receives the wear of the cross head on its outer or upper side, and it is adjustable vertically to change the level of its upper side to compensate for wear and, of course, its length is so proportioned to the stroke of the cross head that it affords a bearing for the cross head throughout its stroke. Near each end the block 11 has in its underside a T-slot 12, the narrow part of the T opening downward to receive the head and shank of a vertical adjusting bolt 13 which passes downward through a threaded hole 14 in the bar 10 with its lower end emerging and suitably formed for the application of a tool to revolve the screw to affect the vertical adjustment of the wear-receiving block 11. I 85 preferably provide the protruding end of the bolt with a triangular head 15 in order to prevent the use upon it of a monkey wrench and compelling the use of the socket wrench which will be kept at the round 90 house, or place of repair so as to avoid the danger of anybody, but the properly authorized person, or workman from interfering with the adjustment. A lock, or jam nut 16 is applied to the portion of the adjusting bolt outside the bar 10. At each end the block 11 rests upon a plate 17, which is seated in and is adapted to fill a transverse slot, or recess 18 in the bar 10, and when the block 11 is moved upward for adjustment purposes, thin plates, or liners are 95 inserted between said plate and the bottom of the groove so as at all times to keep the top of the plate in contact with the underside of the block 11, and thus afford a wide, substantial and efficient support for the bearing block 11. The latter at each side has a vertical lip, or flange 19 which overlaps the outer side of the bar 10, and the supporting plate 17, and to afford access to 100 the latter in its recess when liners are to be applied, the end portion of one of the lips 105

consists of a detachable plate 20 upon whose removal the end of the block-supporting plate 17 is uncovered. Said plate 20 is seated in a recess in the side of the adjustable wear block, and preferably the joint between the vertical wall of the recess and the adjacent edge of said plate is formed by a rib and groove construction so as to afford, with an attaching bolt, a strong and secure connection. The joint between the ends of the adjustable block 11 and the end of the recess in the bar 10, is also overlapped and covered by a short flange, or projection 23 on the two ends of said block, and at each side thereof.

For purposes of construction, by which the bolt-engaging T-slots 12 may be wholly within the body of the block, the latter is made in two longitudinal parts that join 20 on a plane to one side of the bolt heads, the T-slots being formed wholly in one of the two parts and opening on the inner surface of said parts so that when the two parts are together the open sides of the T-slots are 25 closed, and said two parts are firmly joined together by several horizontal bolts, or screws 24 whose heads are counter-sunk so that they will not project beyond the outer side of the block 11, and thus offer no obstruction to the overhanging flange, or lip 30 of the cross head. Preferably the same bolt or screw 24 which unites the two parts of the block is utilized for the attachment of the removable cover plate 20, but I, of course, do not limit myself to that construction, nor, indeed, to any of the details of 35 construction which I have shown in the drawing and have described with particularity, because variation in design and construction may be made which will involve no departure from the scope of my invention. Thus, though I show in the drawings the base or supporting bar 10 as formed of one integral piece, it may be built up of 40 several pieces. The offset ends of the bar may be formed separately from the remainder and the ends and the body portion of the bar joined by vertical bolts that pass through overlapped portions thereof.

50 The manner of adjustment of my guide will be evident from the description that I have already given, and as will be plain, the adjusting operation can be readily and quickly performed and it will also be evident that at all points of its adjustment the cross head bearing block 11 will be solidly and rigidly supported.

Having thus described my invention what I claim is—

60 1. A cross head guide comprising a base member, an adjustable bearing block, a plurality of supporting plates situated between

the bearing block and said base and adjusting means acting upon said bearing block to lift the same from said supporting plates. 65

2. A cross head guide comprising a base member, an adjustable bearing block, a plurality of supporting plates situated between the bearing block and said base, the base having a recess for each of said supporting plates and adjusting means acting upon said bearing block to lift the same from said supporting plates.

3. A cross head guide comprising a base member, an adjustable bearing block, and 75 a plurality of supporting plates situated between the bearing block and said base, the base having a recess for each of said supporting plates, said recess extending from side to side of the base, and the bearing 80 block having a removable cover plate lying over the end of said supporting plate.

4. A cross head guide comprising a base, a bearing block situated in a recess in the base, a plurality of adjusting bolts engaging 85 threaded openings in the base and engaging said block, and a supporting plate at each end of said block and situated in a recess in the base said adjusting bolts acting to lift the block from said supporting plates. 90

5. A cross head guide comprising a base, a bearing block situated in a recess in the base, a plurality of adjusting bolts engaging threaded openings in the base and engaging said block, a supporting plate at each end 95 of said block and situated in a recess in the base, and the bearing block having a removable cover plate lying over the end of said supporting plate.

6. A cross head guide comprising a base, 100 a bearing block situated in a recess in said base, an adjusting screw passing through a threaded opening in the base and having a head that acts upon said block to lift the same, the bearing block having a T- 105 slot to receive said head and the adjacent portion of the screw, the bearing block being composed of members that join on a longitudinal plane, and means for connecting said two members. 110

7. A cross head guide comprising a base, a bearing block situated in a recess of the base that extends from side to side of the base, the bearing block having at each side a flange that overlaps the contiguous portion 115 of the base, a plurality of supporting plates situated between the base and the bearing block and lying between said flanges and means for adjusting the bearing block to compensate for wear of the cross heads. 120

In testimony that I claim the foregoing I have hereunto set my hand.

HUGH H. WALCK.
